WHEEL

Donald J. Reid, Pleasant Ridge, Mich., assignor to Kelsey-Hayes Company, Romulus, Mich., a corporation of Delaware

Filed Apr. 27, 1964, Ser. No. 79,705

Term of patent 14 years

(Cl. D14—30)

FIGURE 1 is an elevational view of a wheel showing my new design;

FIGURE 2 is a sectional view of the wheel of FIGURE 1 taken along the line 2—2 thereof;

FIGURE 3 is a sectional view of a spoke portion of the wheel taken along the line 3—3 of FIGURE 1; and

FIGURE 4 is a reduced scale perspective view thereof with the broken line portions omitted for convenience of illustration.

The dominant features of my design reside in the portions shown in full lines.

I claim:

The ornamental design for a wheel, substantially as shown and described.
